UNITED STATES PATENT OFFICE.

WILLIAM JOHN HASTINGS BEACH, OF WELLINGTON, NEW ZEALAND.

AEROPLANE.

1,018,474.

Specification of Letters Patent. Patented Feb. 27, 1912.

Application filed August 5, 1910. Serial No. 575,769.

To all whom it may concern:

Be it known that I, WILLIAM JOHN HASTINGS BEACH, subject of the King of Great Britain, residing at Wellington, in the Dominion of New Zealand, have invented a new and useful Improved Aeroplane; and I do hereby declare the following to be a full, clear, and exact description of the same.

10 This invention relates to an improved construction of aeroplane that has been designed with the view of obtaining the greatest amount of lifting power with a minimum of wind resistance, and generally 15 to provide for the efficient manipulation of the machine while flying and for its stability upon an even keel.

The essential feature of novelty in the improved machine consists in the combination 20 of two monoplanes arranged one behind the other upon a single frame of triangular cross section and each of which planes is provided with its own means of propulsion.

Other features of the construction consist 25 in the combination with each of such planes of a small plane arranged below it and secured transversely across the base of the frame, and to the combination with each of the main planes of flexibly hinged extensions that normally incline rearward from 30 the back edge of the plane.

In fully describing the invention, reference will be made to the accompanying sheet 35 of drawings, in which:—

Figure 1 is a plan of the machine. Fig. 2 is a side elevation thereof. Fig. 3 is a front elevation. Fig. 4 a plan of the frame and the small planes. Fig. 5 a detail view 40 on an enlarged scale of the frame work of one end of the main plane. Fig. 6 is a side elevation of the machine frame.

In carrying out the invention the frame is made up of a number of triangular members *a* arranged vertically parallel to each 45 other and securely connected together by means of tie bars or girders *b* extending along between their apexes and the extremities of their bases, such girders thus extending from front to rear of the frame. A 50 stable frame is thus provided.

The main planes *c* are arranged to extend transversely across the upper portion of the frame, one at the front and the other at the rear thereof. These planes are made of suitable 55 width and length and are adjusted to extend equally upon both sides of the frame.

Each plane *c* is provided at its extremities with tips or ailerons *d* hinged thereto in such a manner as to be capable of turning up or down to assume varying angles with the surface of the plane. These several ailerons are connected together so as to work in conjunction with each other so that the two on one side of the machine will turn down or up together, while the two on the other side will be given an equal amount of movement but in a reverse direction. These connections are not shown in the drawings as this feature is one well known in connection with the construction of other aeroplanes and forms no feature of the present invention. Each main plane is also provided with a pair of rearwardly extending wings *e* arranged one on each side of the machine frame and hinged to the rear edge 75 of the plane. These wings are hinged and acted on by springs *e'* (Fig. 5) in such a manner that they normally extend downward at a slight incline, as shown in Fig. 2. The springs are so adjusted in tension that when the machine is passing through the air at a high speed the air pressure beneath the wings will force them up so that they will extend uniformly with the surfaces of the planes. Then when the speed is reduced or 85 the flight of the machine is stopped, these wings under the action of their springs, will resume their normal inclined position so that they will impart an elevating tendency 90 to the planes and thereby prevent the machine diving straight down to the ground, but instead, will cause it to glide down at an incline in order that it may settle on its base.

Deflecting planes *f* and *g* are secured one at the front and one at the rear of the machine, such planes being of the well known type in construction and operation and being worked together in the well known way. These planes are used for guiding the machine up or down in its flights the connections between the planes being such that when the front plane is turned up, the rear plane will be turned down a corresponding amount and vice versa.

The machine is also provided with the rudder *h* at its rear, such rudder being to control its flight in the horizontal plane and being also adapted to work in conjunction with the ailerons *d* in the well known manner by means of suitable connections not shown in the drawings.

A small subsidiary supporting plane *j* is

secured across the bottom of the frame beneath each main plane. These planes *j* are made shorter than the main planes so as to permit the air to have free access to the main planes and thus not to interfere with the buoyancy thereof. The planes serve to assist in carrying the weight of the frame and of the driving engine and aviator.

A propeller *k* is mounted in front of each main plane and is secured upon a shaft *l* carried in bearings upon the frame. The two shafts and their propellers are adapted to be driven from the engine or motor carried upon the forward plane *j* and are caused to revolve in opposite directions by suitable gearing *m* connecting the two shafts together.

The frame is mounted on wheeled carriages *n* which are pivotally attached to the frame and provided with the spring cushions *o* interposed between the frame and the carriages so as thus to form cushions against any jar being transmitted to the machine when it alights on to the ground.

The motor will preferably be arranged above the forward small plane *j* while the seat for the aviator and the several controlling levers and wheels will be arranged above the rear small plane *j*. Any passengers or weight carried on the machine will then be placed along the frame between them so that the whole weight carried will thus be evenly distributed throughout the full length of the machine.

It will be seen that the main weight of the machine is all arranged beneath the main planes thereof so that its stability and

capability to keep on an even keel while in flight, will be materially assisted.

What I do claim as my invention, and desire to secure by Letters Patent is:—

1. In aeroplanes, a frame composed of a number of triangular members arranged vertically parallel and having horizontal bottom bases and connected together by tie bars extending along their apexes and bases, two main planes secured across the upper part of such frame, one behind the other a subsidiary short plane secured across the bottom of the frame beneath each main plane, level with said bases and a separate propeller for each of such main planes, substantially as specified.

2. In aeroplanes, a frame composed of a number of triangular members arranged vertically parallel and connected together by tie bars extending along their apexes and bases, two main planes secured across the upper part of such frame one behind the other, laterally extending hinged wings or ailerons on both ends of each main plane, a pair of rearwardly extending hinged wings on each plane, springs for normally holding such wings at a downward incline, and a separate propeller for each plane, substantially as specified.

In testimony whereof, I have signed this specification in the presence of two subscribing witnesses.

WILLIAM JOHN HASTINGS BEACH.
